CLAIM

The ornamental design for a light fixture cross-arm assembly, as shown and described.

DESCRIPTION

FIG. 1 is a perspective view of an embodiment of the invention;

FIG. 2 is an enlarged perspective view of an embodiment of FIG. 1;

FIG. 3 is a front elevational view of FIG. 2;

FIG. 4 is a top plan view of FIG. 2;

FIG. 5 is a side elevational view of FIG. 2;

FIG. 6 is a back elevational view of FIG. 2;

FIG. 7 is a perspective view of another embodiment of the invention;

FIG. 8 is a front elevational view of FIG. 7;

FIG. 9 is a top plan view of FIG. 7;

FIG. 10 is a side elevational view of FIG. 7; and,

FIG. 11 is a back elevational view of FIG. 7.

The lighting fixtures including mounting elements are shown in broken lines for illustration purposes only and form no part of the claimed design.
